UNITED STATES PATENT OFFICE.

JULES HAUVENTTE-MICHELIN, OF NEW BRUNSWICK, NEW JERSEY, ASSIGNOR TO
MICHELIN TIRE CO., OF MILLTOWN, NEW JERSEY, A CORPORATION OF NEW
JERSEY.

DESIGN FOR A TREAD FOR TIRES.

47,892.

Specification for Design.

Patented Sept. 28, 1915.

Application filed July 10, 1915. Serial No. 39,202. Term of patent 14 years.

To all whom it may concern:

Be it known that I, JULES HAUVENTTE-MICHELIN, a citizen of the French Republic, residing at New Brunswick, in the county of Middlesex and State of New Jersey, have invented a new, original, and ornamental Design for Treads for Tires, of which the following is a specification, reference being had to the accompanying drawings, forming a part thereof.

Figure 1 is a top plan view showing my new design; and Fig. 2 a sectional view along the line 2—2 of Fig. 1, showing the new design.

I claim as my invention—

The ornamental design for a tread for tires as shown.

In testimony whereof, I affix my signature.

JULES HAUVENTTE-MICHELIN.
